(57) **CLAIM**

The ornamental design for a surgical guide, as shown and described.

DESCRIPTION

FIG. 1 is a perspective view of a surgical guide, showing my new design;

FIG. 2 is a front elevation view of the surgical guide illustrated in FIG. 1;

FIG. 3 is a rear elevation view of the surgical guide illustrated in FIG. 1;

FIG. 4 is a right elevation view of the surgical guide illustrated in FIG. 1;

FIG. 5 is a left elevation view of the surgical guide illustrated in FIG. 1;

FIG. 6 is a top plan view of the surgical guide illustrated in FIG. 1; and,

FIG. 7 is a bottom plan view of the surgical guide illustrated in FIG. 1.

1 Claim, 5 Drawing Sheets
